UNITED STATES PATENT OFFICE.

JACOB PETRY, OF PITTSBURGH, PENNSYLVANIA.

DENTAL SUCTION PLATE.

Application filed April 18, 1922. Serial No. 554,386.

To all whom it may concern:

Be it known that I, JACOB PETRY, a citizen of the United States, and resident of Pittsburgh, in the county of Allegheny and

5 State of Pennsylvania, have invented a new and useful Improvement in Dental Suction Plates; and I do hereby declare the following to be a full, clear, and exact description thereof.

10 My invention relates to dental suction-plates.

In a patent granted to me October 10, 1911, No. 1,005,296 there is illustrated a dental suction-plate having a plurality of 15 suction-cups permanently secured to the plate, said suction cups being formed of light rubber, and being connected integrally to the plate by a neck-portion of rubber. In a plate of this character, where the cups are 20 connected permanently to the suction-plate, if one of the cups wears out or loses its suction ability it is necessary to obtain an entirely new plate, as all of the cups are connected integrally to the plate, and it is 25 practically impossible to add a new cup to the plate.

The object of my present invention is to provide for the supporting of the suction-cups directly on the dental-plate, each cup 30 being mounted thereon individually so that if it wears out another may be substituted without the services of a dentist, so that by having a supply of these cups on hand the owner of the plate may himself insert a new 35 one whenever it is necessary.

In the accompanying drawing, Fig. 1 is a perspective view of a dental-plate showing my invention applied thereto; Fig. 2 is a plan view of one of the suction cups; 40 Fig. 3 is a section on the line 3—3, Fig. 2; Fig. 4 is a section on the line 4—4, Fig. 2; Fig. 5 is a section on the line 5—5, Fig. 3 looking in the direction of the arrows; and Fig. 6 is an enlarged cross-section of 45 the dental-plate showing the cups in different positions therein.

In the drawing, the numeral 2 designates a dental-plate with the teeth 3 secured therein. Formed in the plate are the seats or 50 recesses 4 which are preferably oblong in shape corresponding to the shape of the cups 5, and said seats are formed with the under-cut portions forming the grooves 6.

Any desired number of these seats may be formed, according to the number of suction-cups required, and the arrangement may be varied according to conditions.

The suction-elements 5 are double, in the sense that there are upper and lower cup sections, the upper cup-section 7 being 60 somewhat thinner than the lower section 8. The lower section has the corrugations 9, formed therein, so that in case the upper and lower sections of the cup are brought into contact with each other they will not 65 stick or adhere, due to the admission of air between the faces of the corrugations 9.

The lower cup-sections are inserted in the seats 4 by compressing the cup slightly, as shown in the left of Fig. 6, so as to insert 70 it in the opening of the seat 4, and when therein the cup is allowed to expand to the position indicated in the center and right of Fig. 6, the lower cup-section fitting down in the undercut grooves 6 of the seat so as 75 to fit snugly therein, and in this manner the cups are securely held in position on the plate by suction.

In this manner I provide not only for the holding of the plate to the roof of the mouth by suction-cups, but the lower sections of the cups also act to connect the cups to the plate, and in this way I am able to dispense with the use of rivets, cement or other fastening means for securing the cups 80 to the plate.

If for any reason, due to pressure, the upper and lower sections of the cup should come in contact they will not adhere, due to the air spaces afforded by the corrugations 90 9 on the lower cup-section.

In case one of the suction-elements becomes worn out, or for any reason loses its suction ability, it is a simple matter for anyone to remove the damaged suction-element and insert a new one without calling 95 on the services of a dentist.

What I claim is:

1. The combination of a plate having a seat formed therein with an undercut 100 groove, and a suction element having upper and lower reversed cup-sections, one cup-section engaging said seat.

2. The combination of a plate having a seat formed therein with an undercut 105 groove, a suction element having upper and

lower reversed cup-sections, the lower cup-section fitting within the seat, and said lower cup section being thicker than the upper section.

5. 3. The combination of a plate having a seat formed therein with an undercut groove, a suction element having upper and

lower reversed cup-sections, the lower cup-section engaging said seat, and one of said cup-sections having corrugations formed on 10 its outer face.

In testimony whereof I, the said JACOB PETRY, have hereunto set my hand.

JACOB PETRY.
